UNITED STATES PATENT OFFICE

166,480

GREASE JAR

Melvin G. Miller, Houston, Tex.

Application March 4, 1946, Serial No. 127,099

Term of patent 14 years

(Cl. D58—25)

To all whom it may concern:

Be it known that I, Melvin G. Miller, a citizen of the United States residing at Houston, in the county of Harris, in the State of Texas, have invented, a new, original, and ornamental Design for a Grease Jar, of which the following is a specification, reference being had to the accompanying drawings, forming a part thereof.

Figure 1 is a side view of the jar showing my new design.

Figure 2 is a side view showing the side opposite that shown in Figure 1; and

Figure 3 is a top plan view.

I claim:

The ornamental design for a grease jar, as shown.

MELVIN G. MILLER.
